UNITED STATES PATENT OFFICE.

WILLIS H. McDOWELL, OF AUBURN, INDIANA.

MACHINE FOR MANUFACTURING CONCRETE BUILDING-BLOCKS.

No. 813,573.

Specification of Letters Patent.

Patented Feb. 27, 1906.

Application filed August 10, 1905. Serial No. 273,660.

To all whom it may concern:

Be it known that I, WILLIS H. McDOWELL, a citizen of the United States, residing at Auburn, in the county of Dekalb and State of Indiana, have invented new and useful Improvements in Machines for Manufacturing Concrete Building-Blocks, of which the following is a specification.

My invention pertains to certain new and useful improvements in a machine for manufacturing concrete building-blocks.

The invention contemplates an improved type of machine of this class wherein the cores are hollow and so mounted as to be moved into and out of the mold, the plastic composition displaced by the entrance of the cores being received on the interior of said cores, from which it may be subsequently removed.

Further, the invention contemplates an improved mounting for the cores in order that they may be operated into and out of the mold without scraping or rubbing the edges of the mold-apertures, attended by the disadvantage of wearing an uneven surface forming an irregular guide for the cores.

Referring to the accompanying drawings, forming a part of this specification, wherein like numerals of reference designate similar parts throughout the several views, Figure 1 is a central vertical sectional view on line 1 1 of Fig. 2. Fig. 2 is a top plan view of my machine. Fig. 3 is a view similar to Fig. 1, but showing the cores as partly inserted within the mold and the pedestal of the machine broken away. Fig. 4 is a perspective view of the core-operating mechanism detached from the machine, and Fig. 5 is a perspective view of a block formed in my improved machine.

In the accompanying drawings, 1 designates a suitable table-framework supported by the pedestal 2. The table - framework consists of two channel-bars 3, arranged in spaced relation. Transverse of the bars and connected to each of the same is a mold-base 4, the latter being of the requisite dimensions and having hinged, as at 5, on its upper face one side 6 of the mold. The opposite side 7 of the mold is hinged to the base 4, as indicated at 8, and the ends 9 10 are hinged, as indicated at 11 12, respectively, to the spaced bars 3 in order that they may be swung outwardly to free themselves of the mold, in conjunction with the sides 6 7, at such times 55 when the block being molded is in condition to be removed from the mold. The side 7 of

the mold is engaged by a member 13, hinged, as at 14, to each of the bars 3 at its lower end and at its upper end being provided with operating-handles 15. Member 13 at each of its ends is provided with a projection 16, which is engaged by the hook-shaped catch 17 of a locking member 18, which consists, essentially, of a bar 19, formed with slots 20, through which pass bolts 21, secured to the end 9 of the mold. Thus a longitudinal movement is permitted bar 19. The opposite end of bar 19 is equipped with a transverse spindle extending on opposite sides of the bar, one end of the spindle carrying the said catch 17 and the opposite end a butterfly-nut 23 and the handle 24, by means of which the bar 19, together with the spindle 22, may be moved inwardly and outwardly to engage catch 17 with projection 16, and thereby lock member 13 in engagement with side 7.

It will be understood that by simply tightening nut 23 the spindle 22 will be locked with respect to bar 19, and the member 13 will thereby be retained in immovable position. Member 13 is equipped with a longitudinal strip of metal 24, which at its ends is formed with catches 25, adapted to engage the ends 9 10, and thereby retain the same against outward movement.

The table-framework is preferably equipped with a support 26 for the purpose of engaging member 13, and thereby restricting the downward movement of the same. To the outer face of side 6 of the mold I secure a pair of parallel spaced rods 27, which are secured to the mold, preferably by means of collars 28' and set-screws 29', the collars being borne by the side. Slidably mounted on these rods 27 is a cross-head 28, which is formed of bar 29, whose ends are penetrated by the rods 27, and with extensions 30, spaced from bar 29 and connected thereto by webs 31 and which are likewise penetrated by rods 27. Inasmuch as extensions 30 are spaced from the ends of bar 29, it will be observed that a rigid support is thus provided for the cores, which, as will presently appear, are borne by the cross-head. As more clearly seen in Fig. 4 of the drawings, bar 29 is provided with two downwardly-extending projections 31 at its ends, which are perforated to receive securing means which pass therethrough and into boss 32, carried by the hollow cores 33. Bosses 32 are each provided with a bolt 34, to the outer or free end of which links 35 are

connected, these links being joined together at their outer ends by connecting means 36, which embody a sleeve interposed between the links, and the rod threaded at both ends 5 passing through the sleeve and the links and provided with nuts (best seen in Fig. 2) in order to impart movement to connecting means 36, and thereby to the cores, through the intermediate connections, as specified. A trans- 10 verse shaft 37 is employed, whose ends are suitably journaled in the bars 3, as indicated at 38, and which carries an arm 39, rigidly related thereto and secured to the said sleeve by connecting means 36. The shaft may be 15 given rotary reciprocal movement by means of a hand-lever 40, which may be secured to the end thereof, as shown in the drawings.

I may provide each core at the front ends 20 and projecting from adjacent the bottoms thereof with guide-lips 45 of the form shown, which are received in openings 46 in the side 7 of the mold. These lips serve to act as a support for the cores when the plastic material is being filled in about the same, and, fur- 25 ther, serve in the capacities of shovels clearing the way for the cores.

In order to restrict the outward movement 30 of the cross-head 28, as well as to provide a means for retaining the rods 27 in their proper spaced relation, I employ a connecting-bar 41, which at its ends is provided with perforated bosses 42, into which extend set-screws 43, which bear against the rods 27, and thereby 35 retain bar 41 in its proper position.

As shown in Fig. 2 of the drawings, I prefer- 40 ably equip the inner faces of the ends of the mold with raised portions 47, which form the recesses 48 in the molded block, as shown in Fig. 5 of the drawings.

The cores are preferably formed as shown, 45 wherein they are provided with an inclined opening 49, preferably having its highest point at the front end of the core. It will be observed, as shown in Fig. 3 of the drawings, that the cores upon entering the mold will displace such of the plastic composition as is disposed in the path of the incoming cores and cause the same to be received within the

core-openings 49, from which it may be sub- 50 sequently removed.

A machine of the type just set forth con- 55 tains but comparatively few parts and may be very readily operated. By unfastening of the locking means the mold ends and sides may be moved away from the block after the latter is in a completed state to allow of the block being removed. As the supporting mechanism for the cores is carried directly by the mold, it will be thereby observed that the relative position of the cores with respect to 60 the mold side is never varied, and consequently the scraping action referred to is entirely avoided.

Having thus fully described my invention, 65 what I claim as new, and desire to secure by Letters Patent, is—

1. In a machine of the type set forth, a mold having openings in one side thereof, rods supported solely from one of the mold sides, a cross-head comprising a bar pen- 70 etrated by said rods, extensions carried by the bar and spaced from the same, and also pen- etrated by said rods, webs connecting the said extensions to the bar, downwardly-extending projections carried by the bar, cores having 75 bosses, means for securing said bosses to said projections, and means for operating the cross-head.

2. In a machine of the type set forth, a core having an inclined opening extending 80 from end to end of the same, a guide-lip carried at the front of the core and below the opening thereof, and a mold having an opening to receive said lip.

3. In combination with a mold, a core 85 formed with an opening, an element of shovel- like form carried by the core to deposit the displaced plastic material in said opening, and means to operate the core.

In testimony whereof I affix my signature 90 in presence of two subscribing witnesses.

WILLIS H. McDOWELL.
